[57] CLAIM

The ornamental design for a combination cutting gauge and guide, as shown and described.

DESCRIPTION

FIG. 1 is a top, front, left side perspective of a combination cutting gauge and guide, showing my new design; a cutting gauge arm is depicted in a gauging position in dashed outline;

FIG. 2 is a bottom, rear, right side perspective view thereof; and,

FIG. 3 is a top perspective in the same direction as FIG. 1 and illustrating my new design being used with an article to be gauged and cut.

The dashed outline depicted in FIG. 3 representing the article to be cut, a tape measure, and a clamp are not part of my claimed design.
